BURNER CONTROL

John M. Wilson, Minneapolis, Minn., assignor to
Minneapolis-Honeywell Regulator Company,
Minneapolis, Minn., a corporation of Delaware

Application September 28, 1940, Serial No. 358,791

14 Claims. (Cl. 158—28)

The present invention relates to apparatus for, and a method of, controlling a burner circuit. More particularly the invention embraces a novel burner control which utilizes a Wheatstone bridge including a resistance which is heat responsive to detect the flame within the furnace or other heating device.

An object of this invention is to provide a simplified burner control which has no moving parts subjected to destructive conditions to thereby obtain a high degree of safety.

Another object, in connection with the preceding object, is to provide such a control utilizing a Wheatstone bridge as a combustion detector, and a safety switch heater connected across the Wheatstone bridge in a manner so that it will respond to a plurality of predetermined conditions.

A further object, in connection with the above objects, is to provide a controller using a Wheatstone bridge in which one leg is responsive to combustion conditions and in which the other leg is heated by an electrical heater that is energized in response to a demand for heat.

Another object is to provide a Wheatstone bridge burner control circuit which is opened and no power is consumed when there is no demand for heat.

The above and other objects will become apparent upon consideration of the accompanying specification, the appended claims, and the drawing, the single figure of which diagrammatically illustrates a burner control circuit including my invention.

A burner controller 10 which may take the form of a burner motor, a fuel delivery pump, a fuel valve, or similar device, and an ignition device 11 are electrically controlled by a condition responsive means 12. The condition responsive member may take the form of a thermostat composed of bimetal 13 which carries a flexible contact arm 14 and a relatively stiff contact arm 15. The contact arm 14 cooperates with a stationary contact 16 and the contact arm 15 cooperates with a stationary contact 17. The contact 16 engages arm 14 prior to engagement of arm 15 and contact 17 when the device is cooled.

A relay mechanism 20 is controlled by the condition responsive means 12. The relay may take the form of a conventional relay coil 21 which moves contact arms 22 and 23. Current for the relay 20 is furnished from a transformer 25 which has a low voltage secondary 26 and a high voltage primary 27.

A safety switch mechanism 30 is provided and 55 which has the characteristic of varying its re-

controls the electric circuit to all of the mechanism of the system. The safety switch comprises a suitably mounted first contact blade 31 and a second contact blade 32 which is inherently biased away from the blade 31. These two contact blades 31 and 32 carry contacts 33 and 34, respectively. The contacts are latched into engaged position against the bias of blade 32 by a thermal member 35. When the thermal member 35 is in the cold position shown, the upper end 36 thereof is beneath the contact blade 32 to maintain the contacts 33 and 34 in engagement. When the thermal element 35 is heated to a predetermined degree the upper end 36 thereof will move to the left from beneath the contact blade 32, thus permitting the contacts 33 and 34 to separate. A conventional trip-free resetter is indicated at 37. When the thermal element 35 moves from beneath the blade 32, said blade will engage the reset button 38 and the other blade 31 will engage the button 39. The buttons 38 and 39 maintain the blades 31 and 32 in spaced relationship thus separating the contacts 33 and 34. A heater 40 is located adjacent the thermal element 35 and operates in a manner to be hereinafter more fully described.

An energizing circuit for the transformer 25 may be traced as follows: from line wire 45 which leads to a suitable source of power, not shown, through the conductor 47, the safety switch 30, wire 48, primary 27 of transformer 25, and conductor 49 to the other line wire 46.

A combustion responsive means 60 takes the form of a Wheatstone bridge having resistances 61, 62, 63, and 64 which may have substantially identical resistivity for a given temperature. The resistances 61 and 62 are preferably adapted to vary similarly in resistivity upon being heated at substantially the same rate and level off in resistivity at substantially the same temperature and ohmic resistance values, for example at 600 degrees Fahrenheit. The supply conductor for the Wheatstone bridge may lead from the relay contact arm 23 through conductor 65 and conductor 66. A second conductor 67 connects the Wheatstone bridge to the line wire 46 and is connected between the two resistances 63 and 64.

The resistance 61 is affected by a heater 70. Whenever the relay 20 is energized an energizing circuit therefor leads from the relay arm 23, wire 65, wire 71, heater 70, wire 72, and adjustable resistance 73, and a wire 74 to the other line wire 46.

The resistances 61 and 62 are made of a metal

sistivity upon a change in temperature. For example, the metal might be nickel or some other compound in which the resistance of the element is raised when subjected to a higher temperature. The two resistances 61 and 62 are subjected to different conditions, the resistance 61 being affected by the heater 70 and the resistance 62 being affected by radiant heat produced by the flame 75 of the burner which is indicated in broken lines. When resistances 61 and 62 are at substantially the same temperature the potentials of points A and B are the same and therefore the bridge is in balance. When one or the other of the resistances is changed, the potential of one of points A or B will be varied with respect to the other and the bridge will be in an unbalanced condition.

The safety switch heater 40 is connected across points A and B by the conductors 80 and 81 and therefore whenever the bridge is unbalanced, current will flow through heater 40.

Operation of the device

A circuit for the fuel delivery means 10 and the ignition means 11 is as follows: from conductor 45, wire 47, safety switch 30, wire 50, contact 51 of the relay 20, contact arm 23, conductor 52, conductors 53 and 54, to the fuel delivery means and the ignition means, and conductors 55 and 56 to the other line wire 46.

By tracing the above circuit it will be noted that when the relay 20 is energized because of the closure of the contacts of the condition responsive element 12 a circuit is established for the fuel delivery means and the ignition means. At the same time, there will be a circuit established for a combustion responsive means generally indicated by the reference character 60.

The thermostat 13 is shown in its satisfied position. Assuming now that the temperature falls, the contact arms 14 and 15 will be moved towards the right. The contact arm 14 will first engage the contact arm 16. However at this time, the relay 20 will not be energized because the contact arm 22 will not have engaged the contact 85. Upon a further decrease in temperature the contact blade 14 will flex to permit engagement of the contact arm 15 with the contact 17. At this time a circuit will be established for the relay coil 21 which may be traced as follows: from the secondary 26 of the transformer 25 through the wire 90, contact 16, contact arm 14, bimetal 13, contact arm 15, contact 17, wire 91, relay coil 21, and wire 92 to the other side of the secondary 26 of the transformer. This circuit will cause the relay to be pulled in and the contact arms 22 and 23 will engage their respective contacts 85 and 51, respectively. A holding circuit for the relay 21 may be traced as follows: from the secondary 26, wire 90, contact 16, contact arm 14, bimetal 13, wire 95, contact 85, relay contact arm 22, wire 96, relay coil 21, and wire 92 back to the other side of the secondary 26. It is seen then that a circuit is provided wherein a thermostat differential is obtained in that contacts 16 and 17 must be engaged to pull in the relay but the relay will be held in independently of the contact 17. In other words, the relay will not again drop out until the contact 14 has separated from the contact 16 thereby providing a temperature differential.

With the relay 20 energized, the fuel delivery means 10 and the ignition means 11 will be energized through the safety switch 30 and the

relay switch arm 23 through the circuit previously traced. Simultaneously, with such energization the Wheatstone bridge will also be energized as well as the circuit to the heater 70 which heats the resistance 61 of the Wheatstone bridge 60.

Assume now that combustion does not properly take place. With the heater 70 energized, heat will be supplied to the resistance 61. When the resistance 61 is heated the resistivity thereof rises and the bridge will therefore be unbalanced between the points A and B. Therefore there will be a current impressed across the safety switch heater 40 and after a predetermined time, for example 90 seconds, the upper end 36 of the thermal timer 35 will move from beneath the blade 32 and permit the contacts 33 and 34 to separate, thus deenergizing the burner circuit as well as the circuit to the Wheatstone bridge 60.

If combustion takes place properly upon energization of the circuit to the Wheatstone bridge 60, the resistor 62 will be heated by the flame. It is preferable to have the resistance 62 heat up at substantially the same rate as the resistance 61. Then, because these two resistances have substantially the same resistivity to temperature coefficients, there will be no unbalance of the Wheatstone bridge and no current will be impressed across the heater 40 for the safety switch 30. Therefore it is seen that a combustion detector is provided which operates upon energization of a burner circuit for immediately detecting the presence of flame. Also it is seen that if combustion does not occur the safety switch will be opened, but if combustion does take place properly the safety switch will not be operated.

Assuming that the burner has started up and has been operating normally as set forth in the preceding paragraph and a flame failure occurs. Previous to this time the resistances 61 and 62 will be at substantially the same temperature so that the bridge is balanced and the heater 40 is inoperative. However, when the flame failure occurs the resistance 62 will very rapidly cool off which unbalances the bridge and causes current to flow through the heater 40 to heat the thermal member 35 and unlatch the safety switch 30 after a predetermined time interval. The switch 30 must then be reset manually before the burner can be restarted.

In the event that any of the resistances 61, 62, 63 or 64 burn out, the Wheatstone bridge would be greatly unbalanced and as a result of the energization of the heater 40 the safety switch 30 would be moved to open position. If the heater 70 or the resistance 73 were burned out, the safety switch would be opened upon the occurrence of normal combustion. Also by the present novel arrangement the heater 40 may be of low ohmic resistance and hence perfectly safe against burning out.

It is seen that I have provided a safety switch in combination with a Wheatstone bridge wherein in different legs of the bridge are subjected to different predetermined conditions. Although I have shown and described one form that my invention may take, it will be clearly understood that many other modifications embodying the principle of the instant device will occur to those skilled in the art, therefore it is to be understood that I am not to be limited by my invention only by that form shown and described but by the scope of the appended claims.

I claim as my invention:

1. A burner control system comprising, in combination, a burner for causing variations in a variable condition, control means responsive to the variations in said variable condition, a circuit controlled by said control means and controlling the operation of said burner, a switch in said circuit, a switch actuator for actuating said switch, a pair of resistances which change their resistivity upon a change in temperature, a heater for one of said resistances controlled by said control means, said other resistance being affected by the flame produced by the burner, and connecting means between said two resistances and said switch actuator for causing said resistances to control said switch actuator.

2. In a fuel burner system, in combination, a burner motor, a circuit therefor, a condition responsive controller in control of said circuit, a safety switch also in control of said circuit, a switch actuator including a heater associated with said safety switch for actuating the same, a pair of resistances which change their resistivity upon a change in temperature, a heater for one of said resistances controlled by said control means, said other resistance being affected by the flame produced by the burner, and connecting means between said two resistances and said switch actuator for causing said resistances to control said switch actuator.

3. The combination with a fuel burner system comprising a burner motor, a controller, a thermal safety switch, and a burner motor energizing circuit controlled by said controller and said safety switch; of a Wheatstone bridge having a plurality of resistance legs which change in resistivity upon a change in temperature, and a heater for said safety switch connected across said bridge, one of said legs being subjected to a first controlled heat condition to vary the resistivity thereof, and at least one other of said legs being subjected to a second heat condition caused by the operation of said burner motor to vary the resistivity thereof.

4. The combination with a fuel burner system comprising a burner motor, a controller, a thermal safety switch, and a burner motor energizing circuit controlled by said controller and said safety switch; of two parallel resistance circuits controlled by said controller and subjected to different predetermined heat conditions to vary the resistivity thereof, a heater for said safety switch joined across intermediate points in said resistance circuits in a manner so that it will respond in accordance with the temperature differential between said circuits, and means controlled by said controller to cause a temperature differential when said burner motor energizing circuit is energized.

5. The combination with a fuel burner system comprising a burner motor, a controller, a thermal safety switch, and a burner motor energizing circuit controlled by said controller and said safety switch; of a Wheatstone bridge having two parallel resistance circuits including two resistors which change their resistivity upon a change in their temperature and two fixed resistances in series therewith to form a pair of intermediate bridge junctions, an electric heater for said safety switch connected between said junctions, and means for differentially heating said resistors to thereby impress a current across said heater to cause operation of said safety switch.

6. The combination with a fuel burner system comprising a burner motor, a controller, a ther-

mal safety switch, and a connecting circuit; of a Wheatstone bridge having two parallel resistance circuits including two resistors which change their resistivity upon a change in temperature and two fixed resistances in series therewith to form a pair of intermediate bridge junctions, a first heater controlled by said controller for supplying heat to one of said resistors to unbalance said bridge when said circuit is energized, the other of said resistors being responsive to the flame of the burner to rebalance said bridge, and a second heater for affecting said safety switch connected across said bridge and being responsive to the unbalanced condition thereof.

7. The combination with a fuel burner system comprising a burner motor, a controller, a thermal safety switch, and a connecting circuit; of a Wheatstone bridge having two parallel resistance circuits including two resistors which change their resistivity upon a change in temperature and two fixed resistances in series therewith to form a pair of intermediate bridge junctions, a first heater controlled by said controller for supplying heat to one of said resistors to unbalance said bridge when said circuit is energized, the other of said resistors being responsive to the flame of the burner to rebalance said bridge, a second heater for affecting said safety switch connected across said bridge and being responsive to the unbalanced condition thereof, and means to adjust said first heater to vary the heating effect thereof upon said one resistor to thereby modify the operation of said second heater.

8. In a fuel burner system, in combination, electrical fuel delivery means, igniting means therefor, an electrical circuit for said delivery and igniting means, a control switch for energizing and deenergizing said circuit in response to variations in a variable condition, control means for also controlling said circuit, timing means associated with said control means, a plurality of resistance circuits, said timing means being associated with said circuits in a manner so as to respond to the difference of resistivity therebetween, and means controlled by said control switch for affecting one of said resistance circuits to vary the resistivity thereof to effect operation of said timing means, another of said resistance circuits being responsive to the heat of combustion effected by said fuel delivery means to thereby compensate said one resistance circuit to render said timing means inoperative.

9. In a fuel burner system, in combination, electrical fuel delivery means, igniting means therefor, an electrical circuit for said delivery and igniting means, a control switch for energizing and deenergizing said circuit in response to variations in a variable condition, control means for also controlling said circuit, timing means associated with said control means, a Wheatstone bridge comprising a plurality of heat responsive legs that change their resistivity, a heater in said circuit, one of said legs being varied in resistivity by said heater at a predetermined rate upon energization of said circuit and another of said legs being varied in resistivity by the heat of combustion caused by said fuel delivery means, and means connecting said timing means across said bridge in a manner so as to respond to an unbalanced condition of the bridge.

10. In a fuel burner system, in combination, a burner provided with igniting means, a control circuit therefor, a control switch for energizing and deenergizing said circuit in response to variations in a variable condition, a safety switch for

also controlling said circuit, thermal timing means associated with said safety switch, a Wheatstone bridge comprising a plurality of legs that change their resistivity upon a change in temperature, said timing means being connected across said bridge in a manner so as to respond to an unbalanced condition of the bridge, and a heater adapted to be energized simultaneously with the energization of said circuit for heating one of said legs to thereby unbalance said bridge to cause energization of said thermal timing means, another of said legs being responsive to the heat of combustion effected by said burner to rebalance said bridge if combustion properly takes place to thereby effectively deenergize said thermal timing means.

11. The combination with a fuel burner system comprising a burner motor, a controller, a safety switch, and a circuit means including said controller and safety switch for controlling said burner motor; of a Wheatstone bridge having a pair of resistors and a pair of intermediate bridge junctions, means controlled by said circuit means for changing the resistance of one of said resistors to unbalance said bridge, another of said resistors being responsive to the flame of the burner to rebalance said bridge, and a safety switch actuator connected to said junctions and being responsive to the unbalance of said bridge to operate said safety switch.

12. The combination with a fuel burner system comprising a burner motor, a controller, a safety switch, and circuit means including said controller and said safety switch for controlling said burner motor; of an electrically operated safety switch actuator, a pair of resistors which change their resistivity upon a change in temperature, means controlled by said circuit means for chang-

ing the temperature of one of said resistors, said other resistor being heated by the flame of the fuel burner, and connecting means between said two resistors and said switch actuator for causing said resistances to control said switch actuator.

13. The combination with a fuel burner system comprising a burner motor, a controller, a safety switch, and circuit means including said controller and said safety switch for controlling said burner motor; of an electrically operated safety switch actuator, a pair of resistors which change their resistivity upon a change in temperature, connecting means between said pair of resistors and said switch actuator, and means in said circuit means controlled by said controller for varying the temperature of one of said resistors for causing electricity to be impressed upon said actuator, the other of said resistors being responsive to fuel combustion to reduce the amount of electricity supplied to said actuator upon the occurrence of a flame.

14. The combination with a burner and an energizing circuit therefor, of control means responsive to a controlled condition for closing said circuit to render said burner operative, a Wheatstone bridge also controlled by said control means and energized when said means closes said circuit, means also controlled by said control means for affecting one leg means of said bridge to vary its resistance and unbalance the bridge, said bridge being rebalanced by another leg means responsive to the occurrence of a flame, a switch actuator connected across said bridge, and a switch also in control of said circuit, said switch being actuated by said actuator in response to the condition of balance of said bridge.

JOHN M. WILSON.
